(57) **CLAIM**

The ornamental design for a bus interior, as shown and described.

DESCRIPTION

FIG. 1 is a forward and leftward facing perspective view of a bus interior taken from outside the bus and showing an entry area of the bus;

FIG. 2 is a leftward facing perspective view of the bus interior taken from outside the bus and showing the entry area of the bus;

FIG. 3 is a downward and slightly forward facing perspective view of the bus interior taken from inside the bus and showing the entry area of the bus;

FIG. 4 is a downward and forward facing perspective view of the bus interior taken from inside the bus and showing the entry area of the bus;

FIG. 5 is a rightward facing perspective view of the bus interior taken from inside the bus and showing the entry area of the bus;

FIG. 6 is a leftward facing perspective view of the bus interior taken from inside the bus and showing a cabin area of the bus that is rearward of the entry area of the bus;

FIG. 7 is a forward and rightward facing perspective view of the bus interior taken from inside the bus and showing the cabin area of the bus that is rearward of the entry area of the bus;

FIG. 8 is a rearward and backward facing perspective view of the bus interior taken from inside the bus and showing the entry and cabin areas of the bus; and,

FIG. 9 is a forward facing perspective view of the bus interior taken from inside the bus and showing the cabin area of the bus.

The broken lines depicting a boundary around the de-emphasized elements, and the de-emphasized elements within, illustrate environmental structure that forms no part of the claimed design.
